UNITED STATES PATENT OFFICE.

LEWIS ELMER DE NEERGAARD, OF PORT CHESTER, NEW YORK, ASSIGNEE, BY MESNE ASSIGNMENTS, TO TECHNOLOGY SALES CO., INC., OF NEW YORK, N. Y.

WINDOW-LOCK.

1,157,767.

Specification of Letters Patent.

Patented Oct. 26, 1915.

Application filed February 10, 1912. Serial No. 676,915.

To all whom it may concern:

Be it known that I, LEWIS ELMER DE NEERGAARD, a citizen of the United States, residing in the city of Port Chester, county 5 of Westchester, and State of New York, have invented certain new and useful Improvements in Window-Locks, of which the following is a full, clear, and exact description, reference being had to the accompanying drawings, forming part of this specification.

This invention relates to improvements in window locks and particularly to that class of window locks comprising a stationary 15 member attached to the inner sash of a window and two clamping members slidably connected thereto, adapted to clamp the device between the outer sash and the frame molding of the same so as to secure the 20 sashes in position and to prevent the opening of the window from the outside.

The primary object of this invention is to provide a window lock which shall be strong and durable and which shall entail 25 a low cost of manufacture, at the same time being attractive both in design and appearance.

A further object of this invention is to provide a window lock which shall be effective in locking both the outer and the 30 inner sash of a window, and that besides insuring the safety of the same shall effectively prevent the rattling of the window due to the wind.

Another object of this invention is to provide a window lock of a simple and inexpensive construction capable of exerting a 35 powerful grip, at the same time having a wide range of adjustment, and therefore adapted for use in different sizes of windows.

A still further object is to provide a window lock for the purposes mentioned having means for securing the same to the inner 45 sash of a window in order to prevent the easy removal of the same, and which shall have convenient means for operating the same in a quick manner.

An additional object of this invention is 50 to provide a window lock having two clamping members provided with serrations in two opposite senses and capable therefore of locking the sashes of a window against motion in opposite directions.

With these and other objects in view as 55 will more fully appear as the description proceeds, this invention consists in certain constructions and arrangements of parts as will be hereinafter described and claimed in the appended claims.

The main object of window locks of the character to which this invention refers, is to fasten the window in any position, and to prevent the same from being opened from the outside. Several devices constructed to 60 this end have come to my notice, but I have found that these are all more or less inconvenient for use, especially on account of lack of means for fastening the devices to any part of a window to which the same is 65 applied. The consequence of this is that the device can be easily removed and stolen, and at every occurrence in which the window is operated, the removal and the replacing of the safety lock requires a certain amount 70 of time and attention. These devices are also generally operated by a separate key which is sometimes lost or misplaced; this is quite good for locking windows for a certain length of time, for instance when a 75 residence is closed, but for every day use, the lack of attached operating means is a serious inconvenience in a device of this kind.

The disturbing effects of the rattling of 80 window sashes due to the wind are also generally known, and in designing my safety lock, I have found it convenient to embody into the construction of the same, means which shall effectively prevent this 85 serious annoyance. While my device can exert a most powerful grip such as will be quite sufficient for the purposes for which the same is intended, in the manufacture of the same I have carefully avoided the use 90 of threaded parts which are necessarily costlier than die produced sheet metal parts; and I also have sought to avoid the use of parts prominently projecting from the surface of the device, which render the same 95 clumsy in design and less attractive in appearance.

Referring to the drawings, Figure 1 is a front view in elevation of a device built in accordance with my invention in which one 100 of the clamping members slides within the other; Figs. 2, 3, 4, and 5, are respectively a plan sectional view, a side view in eleva-

tion from the inner end; a detail side view in elevation partly broken away from the outer end; and a sectional side view in elevation of the same; Fig. 6 is a plan view of 5 a key or wrench which may be used for operating my device; Fig. 7 is a side view in elevation of the same; Fig. 8 is a perspective view illustrating the application of a device built in accordance with my invention, 10 of a somewhat simpler design than the device shown in Fig. 1, to a window of the ordinary kind; Figs. 9 and 10 are respectively a plan view partly sectioned, and a detail view in elevation partly broken away, 15 illustrating the application of a device built along similar lines, for clamping together the frames of Venetian blinds; Fig. 11 is a plan sectional view of a device slightly different in construction from that shown in 20 Fig. 8; Fig. 12 is a front view in elevation of the same fitted with an operating articulated wrench; Figs. 13, 14 and 15 are respectively a side sectional view; a detail side view in elevation from the outer end; and a side view in elevation from the inner end 25 of the device illustrated in Figs. 11 and 12; Fig. 16 is a front view in elevation of a similar device having an attached handle; Fig. 17 is a front view in elevation of a device built in accordance with my invention 30 provided with a different kind of operating means; Fig. 18 is a plan sectional view of the same; Fig. 19 is a detail side view in elevation showing the way of retaining the operating screw in position in the devices 35 shown in Figs. 17 and 18; and Fig. 20 is a detail front view in elevation partly broken away, illustrating a different form of interlocking cam-acting member and wrench 40 or key for the same.

In the device shown in Figs. 1 to 5, 25 designates a stationary member serving as a bearing plate or backing element and provided with a lug or projection 26, having 45 passages 27 for the screws fastening the device to the inner sash of a window. The device as represented is supposed to be mounted on a window of the usual type in which the inner sash occupies the lower section 50 of the window when the same is closed. Lug or projection 26 will therefore rest on the top railing of the inner sash and will be retained thereon by fastening screws or by any other suitable means.

55 28 is a rear clamping member longitudinally movable on said stationary member 25, provided with a serrated flange 29.

30 designates a front clamping member provided with a serrated flange 31 slidably 60 connected to said member 28 by means of retaining flanges 32, 33, or by any other suitable means.

34 is an operating member provided with cam-acting slots 35, 36, and pivotally mount-

ed in 37 in any suitable manner, for instance, 65 by means of a rivet 38 attached to the stationary member 25, as clearly shown in Fig. 2.

In the construction shown rear clamping member 28 is provided with slots 39, 40, 41, 42, respectively accommodating lugs 43, 44, 45, 46, projecting from the front surface of stationary member 25. The said slots are considerably longer than the said lugs, and they therefore allow the sliding longitudinal motion of member 28 in relation to stationary member 25. As I have stated, member 30 is in its turn slidably connected to member 28, and when assembled the different parts are held together by rivet 38. 80

Member 28 is provided with a stud or rivet 47 projecting through slot 35, and member 30 is provided with a stud or rivet 48 projecting through slot 36; it can be clearly understood by examining the drawings that if member 34 is caused to rotate on its pivot 38, slots 35, 36 will cause the in or out motion of the members respectively engaged by means of the action exerted by said slots on the studs or rivets respectively 90 inserted therethrough.

In the device just described, the range of adjustment of each member is given by the radial difference between the inner and the outer points of its controlling slot; and its 95 total adjustment will be the sum of the two individual adjustments. I have found that for all ordinary purposes this arrangement gives a range wide enough to make the device suitable for any size window, at the 100 same time exerting a most powerful clamping action.

It is obvious that the more development each slot will have for the same amount of motion of the member controlled thereby, 105 the more powerful the grip will be on account of the diminished angle of action of the cam-surface acting against the rivet or stud. Therefore in certain instances where a limited range of adjustment is sufficient, a 110 half a revolution or less of member 34, conveniently accomplished by means of a handle or wrench integral therewith, will be sufficient for operating the same. In other instances it may be necessary to rotate member 34 for more than half a revolution in order to render the device useful for a 115 larger size window, and in these instances it may be preferable to operate the device with a separate handle or wrench 49, provided 120 with prongs 50, such as illustrated in Figs. 6 and 7. To this end member 34 will be provided with suitable openings or notches 51 adapted to receive prongs 50 of said operating handle 49. 125

In Fig. 8 I illustrate a device similar to that represented in Fig. 1 attached to the lower sash of a window by means of screws

52 and the operating member of which 53 is provided with peripheral notches 54 interlocking with the operating key or wrench.

From the way in which the device is mounted on a window, it can be seen that any key or handle integral with the operating member and projecting beyond its periphery would scarcely allow more than half a revolution of the same to be made, since 10 said projecting handle or key would strike at the two opposite ends of its course against the top of the inner sash. Such is the case for instance in connection with the device shown in Fig. 16, which will be at a later 15 point described.

Referring again to Figs. 1 to 5, it is seen that flange 29 is arranged to clamp against the inner frame molding of a window, while flange 31 is arranged to clamp against the 20 inner surface of the outer sash, and is therefore made narrower in order not to deface the same. Said flanges are both provided with serrations engaging the respective surfaces so as to prevent the window from being 25 operated from the outside. In such devices as have come to my notice and built for the same purposes, these serrations are provided in one sense or direction only, and I have found that while the devices are very effective 30 in preventing the motion of the outer sash in one direction, the same can be moved in the opposite direction with comparative ease; I therefore prefer to provide the clamping flanges with serrations 55 in one 35 sense, and serrations 56 in the opposite sense, so that the window will be securely locked against movement in both directions.

In Fig. 1, I show operating member 34 provided with teeth 57 along its circumference 40 against which rests a spring 58 attached to a lug or projection 26. The object of this is to illustrate means which may be provided when desired to hold the device in its clamped position, further insuring the 45 safety of the same; in fact, teeth 57 are so formed that the same will permit the motion of member 34 in the clamping direction, and spring 58 will prevent any return motion of the same unless the same be depressed by 50 hand or otherwise detached from the same. When properly modified my device can also be applied to clamp together from the inside, the so-called Venetian blinds, so as to prevent their being opened; Figs. 9 and 10 refer 55 to such a modified device in which the clamping flanges 59, 60 are serrated on the inside, and exert an inward clamping action to hold together the uprights 61, 62, of the blinds.

60 From the foregoing it is seen that I provide a device which can effectively clamp a window in any position, and at the same time be secured to the same; moreover, the securing of the stationary member of my de-

vice to the inner sash of the window will 65 effectively prevent the rattling of the same due to the wind, and will thus avoid the cause of much noise and annoyance.

Figs. 11 to 15 refer to a slightly different construction of my device which I have 70 found preferable to the one formerly described, on account of its greater solidity and of its lower cost of manufacture. In the said figures is also illustrated a form of articulated wrench which may be also 75 used in connection with any of the devices shown when desired.

In the said figures both the rear clamping member 63 and the front clamping member 64 are slidably connected to a stationary 80 member 65, and retained thereby by means of flanges 66, 67, 68, 69, or by any other suitable means. Said stationary member 65 is provided with a lug or projection 70 used in the manner heretofore described, which 85 secures the device on the inner sash of the window to which the same is applied.

The operation of this device is in all respects quite similar to the operation of the device represented in Figs. 1 and 8, but 90 the construction shown, where both clamping members are retained by the stationary member by means of flanges integral with the same, is much stronger and preferable to the one formerly described in every respect.

71 is a slotted operating member pivoted on a rivet or stud 72, and provided with notches 73; on the same is also pivoted part 74 of an operating wrench which may be 100 used in connection with my device at the end of which 75 is hinged or otherwise pivotally connected handle 76, provided with a tongue or key 77 adapted to engage notches 73. By means of this wrench, operating 105 member 71 can be rotated through as wide an angle as desired.

In Fig. 16 I illustrate a device similar to that shown in Fig. 12 inserted in clamping position; the cam-acting member however, 110 in the style shown has an operating handle integral with the same, and consequently the slots in the same are limited to substantially half a turn, this being all that is possible to effect in a device having a rigid projecting 115 handle integral with the cam-acting member, for the reasons hereinbefore stated.

Figs. 17 to 19 illustrate a device substantially similar to that shown in Fig. 12, but embodying different operating means. In 120 this, 78 is a stationary member which may be attached to the inner sash by means of lug or projection 79; 80 is the rear clamping member and 81 is the front clamping member; said clamping members are slidably mounted on said stationary member and retained by the same by means of flanges, 82, 83, 84, 85. Each clamping mem-

ber is provided with a bracket 86, 87, through which is mounted a left and right hand operating screw 88, the middle portion of which 89 is inserted through a slot 90 provided in a lug 91, centrally projecting from the surface of part 78 and preventing side motion of said operating screw.

The use of an operating or clamping screw in sash-holding devices hitherto proposed is not new and no claim is made to this feature alone. The combination of an operating screw with a device of the type herein disclosed comprising a stationary member attached to the inner window sash and slideable clamping members, however, is new and the same may be adopted when an exceptionally strong clamping action is desired; in the majority of cases however, the use of a screw is quite unnecessary, and I prefer to use the cam-slotted member shown in the other drawings.

As I have heretofore pointed out, there are instances in which it is convenient that the devices be operated by a separate key or wrench; while in many other cases it is preferable that the operating key or wrench be integral with the devices so that the same may be readily operated for ordinary purposes. In Figs. 20 and 21, I illustrate a form of operating key or wrench embodying the advantages of both the stationary key and the removable one.

In said figures, 92 is a cam-slotted member adapted to operate one of the devices shown, and provided with lugs or projections 93 slightly curved inward and then outward, just enough to give some resiliency to the same. 94 is a wrench provided with notches 95 adapted to interlock with said lugs or projections 93, and built so as to require a small pressure to be snapped in position between two opposite lugs and to be retained by the same. Said wrench is therefore adapted to be retained by the device for all ordinary requirements and to perform thus the functions of a handle integral with the cam-acting member. When it is necessary or desirable, said handle can be easily removed and stored away for further use.

Having thus described and ascertained the nature of my invention what I claim as new and desire to secure by Letters Patent of the United States is:

1. A window lock comprising a stationary bearing member, two clamping members mounted thereon and slidably connected thereto, and cam-slotted means for operating said clamping members; for the purposes as set forth.

2. A window lock comprising a stationary bearing member having means for securing the same to the inner window sash, two clamping members mounted thereon and

slidably connected thereto, and cam-slotted means for operating said clamping members; for the purposes as set forth. 65

3. In a window lock the combination of a stationary bearing member having means for securing the same to the inner window sash, two clamping members mounted thereon and slidably connected thereto provided with serrated flanges, and cam-slotted means for operating said clamping members; for the purposes as set forth. 70

75 4. In a window lock the combination of a stationary bearing member, two clamping members mounted thereon and slidably connected thereto, and cam-slotted means mounted on said stationary bearing member for operating said clamping members.

5. In a window lock the combination of a stationary bearing member having means for securing the same to the inner window sash, two clamping members mounted thereon and slidably connected thereto provided with serrated flanges, and a cam-acting member pivotally mounted on said stationary bearing member operating said clamping members; for the purposes as set forth. 85

90 6. In a window lock the combination of a stationary bearing member, two clamping members mounted thereon and slidably connected thereto, a slotted cam-acting member pivotally mounted on said stationary bearing member, and members projecting from the surface of said clamping members through said slotted cam-acting member, and controlled thereby, for operating said members; for the purposes as set forth. 95

100 7. In a window lock the combination of a stationary bearing member having means for securing the same to the inner window sash, two clamping members mounted thereon and slidably connected thereto having serrated flanges, a slotted cam-acting member pivotally mounted on said stationary bearing member, and members projecting from the surface of said clamping members through said slotted cam-acting member, and controlled thereby, for operating said members; for the purposes as set forth. 105

110 8. In a window lock the combination of a stationary member having means for securing the same to the inner window sash, two serrated clamping members mounted thereon and slidably connected thereto, a cam-acting member pivotally mounted on said stationary bearing member operating said clamping members, and means for operating said cam-acting member; for the purposes as set forth. 115

120 9. In a window lock the combination of a stationary member, two clamping members slidably connected thereto, a cam-acting member pivotally mounted on said stationary member controlling said clamping members, and an articulated wrench pivoted co- 125

axially with and secured to said cam-acting member, for operating the same; substantially as set forth.

10. In a window lock the combination of 5 a stationary bearing plate having means for securing the same to the inner window sash, two clamping members having flanges provided with oppositely engaging serrations, a slotted cam-acting member pivotally mounted 10 on said stationary bearing plate, members projecting from the surface of said clamping members through said slotted cam-acting member, and controlled thereby, for operating said members, and means for operating 15 said cam-acting member; substantially as described, and for the purposes as set forth.

11. A window lock comprising a bearing plate, means for securing said plate in a vertical position on a window sash, a pair of 20 clamping plates slidably held by said bearing plate, and means for simultaneously sliding said clamping plates in opposite directions into or out of clamping position.

12. A window lock comprising a bearing 25 plate, means for securing said plate in a vertical position on a window sash, a pair of clamping plates slidably held by said bearing plate and provided with serrated gripping portions, an operating member rotatably mounted on said bearing plate and provided with curved slots, and projections on 30 said clamping plates engaging said slots, whereby said clamping plates may be moved into or out of clamping position.

35 13. A window lock comprising a bearing

plate, means for securing said plate in a vertical position on a window sash, a pair of clamping plates slidably held by said bearing plate and provided with serrated gripping portions, an operating member rotatably mounted on said bearing plate and provided with curved slots, projections on said clamping plates engaging said slots, whereby said clamping plates may be moved into or out of clamping position, and adjustable 40 means engaging said rotatable operating member to prevent reverse rotation thereof when said clamping members are in clamping 45 position.

14. A window lock comprising a stationary backing or bearing member, clamping members slidably held by said bearing member, cam-slotted means mounted on said bearing member for moving said clamping members into or out of clamping position, and 50 means for retaining said clamping members in clamping position.

15. A window lock adapted to be secured to the lower sash of a window comprising a 55 backing plate provided with means for securing said plate vertically upon and transversely of said upper rail, clamping plates slidably mounted on said backing plate, and a rotatable operating member engaging said clamping plates and arranged to move the 60 same into or out of clamping position.
